UNITED STATES PATENT OFFICE.

MARTIN K. HENCH, OF CAMDEN, NEW JERSEY, ASSIGNOR OF ONE-HALF TO LEON G. BUCKWALTER, OF MERCHANTVILLE, NEW JERSEY.

APPARATUS FOR MANUFACTURING WASHERS.

1,381,462.

Specification of Letters Patent. Patented June 14, 1921.

Application filed December 31, 1919. Serial No. 348,546.

To all whom it may concern:

Be it known that I, MARTIN K. HENCH, a citizen of the United States, residing at Camden, county of Camden, State of New Jersey, have invented a new and useful Apparatus for Manufacturing Washers, of which the following is a specification.

It is the object of my present invention to devise a portable punch and washer cutter which can be used in conjunction with any desired or conventional type of power presses such as is now commonly used in drop forging plants, for example, hydraulic presses of any description, either of a hydraulic or a steam hydraulic type, or my apparatus can be used with a steam forge or a drop forge.

The portable punch and washer of my present invention can be readily transferred from one place to another or from one press to another suitable for the sizes of washers which it is intended to manufacture, and the apparatus can be moved around from shop to shop and used wherever the conditions demand so that it can be used in one shop for a few days or a week and then transferred to another shop.

The dies are easily and quickly changed in order to provide for the manufacture of different sizes of washers.

One of the chief advantages of my invention is that it can be used in bridge shops, structural metal shops, railroad repair yards, shipyards and in all places where a number of washers are used but in quantities insufficient to warrant the purchasing of a large and costly machine to be used exclusively for the manufacturing of washers and which must be made permanent and is of such size that it must be kept in the place in which it is first installed.

A machine constructed in accordance with my invention can be constructed at an expense of a few hundred dollars.

With the above in view my invention in its broad and generic scope comprehends a novel method of forming washers and a novel construction of a portable punch and washer cutter in which the washer is formed by a single operation from the stock or sheet material of any desired thickness.

Other novel features of construction and advantage will hereinafter more clearly ap-

pear in the detailed description of my invention.

For the purpose of illustrating my invention, I have shown in the accompanying drawings one form thereof which is at present preferred by me, since the same will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in perspective, a conventional type of a press showing in conjunction therewith a portable punch and washer cutter, embodying my invention.

Fig. 2 represents a top plan view of my device.

Fig. 3 represent a section on line 3—3 of Fig. 2.

Fig. 4 represents a section on line 4—4 of Fig. 2.

Fig. 5 represents a section on line 5—5 of Fig. 3.

Fig. 6 represents a section on line 6—6 of Fig. 3.

Fig. 7 represents, in section and diagrammatically, the position that certain of the parts assume when in position for setting up the punch.

Fig. 8 represents, in section and diagrammatically, the position certain of the parts assume when the punching operation is about to begin.

Fig. 9 represents, in section and diagrammatically, the position certain of the parts assume when the punching operation is completed.

Fig. 10 represents, in section and diagrammatically, the position certain of the parts assume when the stripping operation is about to commence.

Fig. 11 represents, in section and diagrammatically, the position certain of the parts assume after the punching operation has been completed and the punch is at the top of its stroke.

Fig. 12 represents a section on line 12—12 of Fig. 2.

Fig. 13 represents in section, a portion of the apparatus showing one manner in which

it can be modified to form washers of a different size from that produced by the construction seen in the other figures of the drawings.

5 Similar numerals of reference indicate corresponding parts in the figures.

Referring to the drawings:—

10 1 indicates a portable punch and washer cutter embodying my invention, and adapted to be employed in conjunction with any conventional or desired type of a press 2, as indicated in dotted lines in Fig. 1, it being understood that the device is supported on the base plate 3 of the press and can be 15 readily transported as a unit of structure from one press to another or from one place to another in accordance with conditions and requirements met with in practice. 4 designates the base plate which is apertured 20 to receive the lower ends of the spring columns 5 which are connected thereto by means of the bolts 6 which extend through the base plate and into the columns as will be understood by reference to Figs. 5 and 25 6, there being four of these columns employed in the present instance.

The upper ends of the columns 5 pass through the apertures 7 in the head plate 8, see more particularly Figs. 2 and 12, and 30 an aperture 7 opens into an enlarged bore 9 which forms with the aperture 7 a shoulder 10 which serves as a stop to limit the upward movement of the head plate 8 which is occasioned by the springs 11, encircling the 35 spring columns 5 and interposed between the base plate 4 and the head plate 8. The spring columns 5 at their upper ends are of reduced diameter and threaded in order to receive the nuts 12 which latter are provided 40 at their periphery with a desired number of vertically disposed slots 13. Each of the nuts 12 is retained in its adjusted position by means of a key 14 which extends into one of the slots 13 within the bore 9 and at its upper end it is laterally deflected and terminates in a downward extension which receives a bolt 15 which is in threaded engagement with the head plate 8 in order to retain the key 14 in position.

45 50 16 designates stripper posts the lower ends of which are secured in any desired manner with respect to the base plate 4, in the present instance being in threaded engagement therewith. The upper ends of the stripper posts extend into apertures in the head plate 8 and are threaded to receive the nuts 18 which are provided with the vertically disposed slots 19 which terminate a desired 55 distance above the bottom of the nuts 18, as 60 at 20, see more particularly Fig. 3, to form stops.

65 21 designates keys preferably corresponding in construction to the keys 14 and secured in position by means of bolts 22 in threaded engagement with the head plate 8.

A key 21 extends into a slot 19 in a nut 18 and prevents the nut from rotating in order to secure it in its adjusted position, and it will be apparent that if desired the nuts 18 can also serve as stops to limit the downward movement of the head plate 8 as will be apparent from Fig. 3 of the drawings.

70 23 designates the upper stripper head which is apertured as at 24 in order to adapt it to slide on the stripper posts 16, the stripper posts being provided with an enlarged bearing 25, see Fig. 3.

75 The head plate 8 has an aperture 26 therethrough which at its upper end is of enlarged diameter as indicated at 27 in order to receive the enlarged head 28 of a head collar 29 which is locked in position by means of a tongue and groove connection 30 with the head 31 which latter is made in two sections and secured together by means of 80 fastening devices 32, such as for example bolts and nuts, see Figs. 3 and 4.

85 It will be understood from Fig. 4 that by such construction the head collar has a tongue fitting into a groove in the head, and 90 the head has a tongue fitting into a groove in the head collar.

95 33 designates the die which is provided with an outwardly extending flange 34 to seat in slots 35 in the head 31, the die being 100 preferably of circular formation. 36 designates fastening devices passing laterally through the lower portion of the head section to secure the die 33 in position. The head collar 29 is provided with an aperture 105 37 through it which is of enlarged diameter as at 38 in order to receive the head of the upper punch 39. The upper punch 39 is of reduced diameter as at 40 thereby forming a shoulder 41. The lower end of the upper 110 punch 39 is still further reduced in diameter as at 42. The upper stripper head 23 is recessed as at 43 in order to surround and overlap the upper end of the stripper 44. The upper stripper head 23 is provided with a slot 45, see more particularly Fig. 5, which registers with a slot 46 in the lower stripper 44 and in this slot is placed a key 47 which is held in place by means of a set screw 48, it being understood from Fig. 5 that a slot 115 and a key is provided at opposite sides of the upper stripper head.

120 The fastening devices 36 carry I-bolts 49 which pass through the liners 50 and the lower stripper 51 and are provided with nuts 52 which latter are retained in position by means of lock washers 53 of any desired type. The lower stripper 51 is slidably mounted on the lower punch 54 which latter is apertured as at 55. The lower punch 54 125 is of differential diameter at its lower end, and is seated in the base plate 4 and secured in position therein by means of a bolt 56, see more particularly Fig. 4, from which it will be seen that the forward end of the bolt 56 130

extends into a recess in the outer wall of the lower punch.

57 designates emergency stop plates which are secured to the base plate 4 by means of 5 dowel pins 58, see more particularly Fig. 3. The upper stripper head 23 is provided with an annular recess 59 in order to provide the proper amount of play between the stripper head and the punch, see Fig. 4.

10 60 designates the stock or sheet material which is to be punched, and 61 designates the finished washer, the blank or portion which has been removed to form the center hole in the washer being designated by 62.

15 My novel apparatus can be readily changed to produce washers of different sizes as will be understood by reference to Fig. 13 to which attention is now directed, and since certain of the parts are the same 20 as those already described, I have identified such parts by the same reference characters as used in the other figures of the drawings.

The head collar 29 has mounted in it an upper punch holder 63 which is recessed as 25 at 64 to receive the head 65 of the upper punch 66, and above the head 65 is placed an upper punch block 67. The stripper head 23 has connected with it in a similar manner to that already described in connection 30 with the upper stripper 44 an upper stripper 68 which is guided in the die 69 which latter is carried by the head 31. The base plate 4 has seated in it a lower punch holder 70 which is secured therein by means 35 of a bolt 71, and the upper end of the punch holder 70 is provided with an inwardly extending flange 72 which overhangs the base flange 73 of the lower punch 74, which latter rests on a lower punch block 75 positioned 40 within the punch holder 70.

The operation of my novel construction of portable punch and washer cutter will now be readily apparent to those skilled in the art to which this invention appertains and is 45 as follows:—reference being now directed more particularly to Figs. 7 to 11 inclusive of the drawings.

When the parts are in the position seen in Fig. 7, the upper punch and its adjuncts 50 are shown at the top of their stroke and the stock and the parts are in the position for setting up the machine to cut the size of washers desired by changing the punches, die, strippers, and nuts and proper thickness 55 of liners to give the required travel and clearance.

In the position seen in Fig. 7 the head 31 carrying the upper punch 39 and the die 33 is at the top of the stroke and against the 60 stop nuts 12 on the spring columns 5. The lower stripper 51 also carried by the head 31 is shown as having its top flush with the top of the lower punch 54. The upper stripper head 23 and the upper stripper 44 is 65 also at the top of the stroke, the upper strip-

per head contacting with the stop nuts 18 on the stripper posts 16.

Assuming now that the portable punch has been placed in a press of any desired or conventional construction, the stock is inserted as seen in Fig. 7 and the press is started. As the upper head plate 8 and the upper punch 39 move downwardly the upper stripper 44 and the die 33 as well as the lower stripper 51 move downwardly into the 75 position seen in Fig. 8. On the continued downward movement of such parts they assume the position seen in Fig. 9 at which time the punching operation is completed and the washer 61 has been formed from the 80 stock 60, it being understood that such downward movement of the parts causes the compression of the springs 11.

In this position seen in Fig. 9, the upper punch 39 and the die 33 have cut through 85 the stock 60 which is forced over the outside of the lower punch 54 and below the top of such lower punch. The finished washer 61 is apparently resting on the lower punch 54 and held down only by the weight of the 90 upper stripper head and the upper stripper 31 but it is actually wedged tightly between the upper punch 39 and the die 33 and considerable force is required to strip it from the punch 39 and the die 33. The blank 62 95 is forced down inside the lower punch 54 and will eventually drop or be forced out of the enlarged clearance hole in the lower punch. In this position the springs are compressed almost solid in order to store up 100 energy sufficient to actuate the upper stroke of the machine and do the stripping.

In Fig. 10, the parts are shown in the position which they assume on the upward stroke and about to start stripping. On the 105 upward stroke the upper stripper 44 which rests against the washer carries up the upper stripper head 23 until it strikes the stop nuts 18 and its movement and that of the washer is arrested. The head 31 carrying the upper punch 39 and the die 33 continues to move upwardly by force of the springs 11 until they are clear of the washer 61 which frees the washer, and the latter drops upon the stock actually or nearly over the 110 hole left in it by the stock. At the same time, the lower stripper 51 carried upward by the head 31 moves the stock off of the lower punch. The upper stroke continues until the head 31 through its head plate 8 is 115 arrested by the stop nuts 12.

In Fig. 11 the stock is shown as stripped off of the lower punch 54 and lying on the lower stripper 51 so that the stock can be moved along into position for having another washer punched from it. This completes the cycle of the operation.

The emergency stop plates 57 prevent damage to the machine in case of an excessive downward stroke. It will be noted that 130

the upper stripper 44 and upper stripper head 23 drop by gravity to such position to give a clearance between the combined thickness of the stock and the washer, thus permitting free movement in shifting the stock to a new position for continuing the punching. The spring columns 5 act as guide bars for centering the upper and lower punches and the die, and their mating is further insured by having the diameter of the hole in the lower stripper 51 larger than the outside diameter of the lower punch 54. The capacity of the springs 11 is such as to take care of the largest size washers and for smaller washers the capacity of the springs can be reduced by removing two diagonally opposite springs. For punching the smaller sized washers modified forms of punches and holders with fillers or liners are employed in order to reduce the amount of high grade steel employed in the cutting members.

Having thus described my invention, what I claim as new and desire to secure by Letters Patent, is:—

1. A portable apparatus for making washers and adapted to be placed in a press, comprising a fixed punch, a movable punch, a head in which said movable punch is mounted, a die carried by said head, an upper and a lower stripper carried by said head, and means to effect the relative movement between said fixed punch and the movable punch and die.

2. An apparatus for making washers, comprising a fixed punch, a movable punch, a head by which said movable punch is carried, a die carried by said head, an upper and a lower stripper carried by said head, means to move said movable punch and die toward said fixed punch, and means to move said movable punch and die away from said fixed punch.

3. A portable apparatus for making washers, comprising a fixed punch, a movable punch, a head by which said movable punch is carried, a die carried by said head, an upper and a lower stripper carried by said head, means to move said movable punch and die toward said fixed punch, and resilient means to move said movable punch and die away from said fixed punch.

4. A portable apparatus for making washers, comprising a fixed punch, a movable punch, a head in which said movable punch is mounted, a die carried by said head, an upper and a lower stripper carried by said head, means to effect relative movement between said fixed punch and the movable punch and die, and means to limit the upward movement of said movable punch and die.

5. A portable apparatus for making washers, comprising a fixed punch, a movable punch, a head in which said movable punch is mounted, a die carried by said head, an

upper and a lower stripper carried by said head, means to effect relative movement between said fixed punch and the movable punch and die, and means to limit the upward movement of said strippers. 70

6. A portable apparatus for making washers, comprising a fixed punch, a movable punch, a head in which said movable punch is mounted, a die carried by said head, an upper and a lower stripper carried by said head, means to effect relative movement between said fixed punch and the movable punch and die, means to limit the upward movement of said movable punch and die, and means to limit the upward movement 80 of said strippers.

7. An apparatus for making washers, comprising a base plate, columns carried by said base plate, a head plate guided on said columns, nuts adjustable on said columns 85 to limit movement of said head plate in one direction, an upper punch mounted in said head plate, a head connected with said head plate, a die and an upper and a lower stripper carried by said head plate, a fixed punch, 90 and means to effect relative movement between said head plate, upper punch, die and strippers and the fixed punch.

8. An apparatus for making washers, comprising a base plate, columns carried by said base plate, a head plate guided on said columns, nuts adjustable on said columns to limit movement of said head plate in one direction, an upper punch mounted in said head plate, a head connected with said head plate, a die and an upper and a lower stripper carried by said head plate, a fixed punch carried by said base plate, and means to effect relative movement between said head plate, upper punch, die and strippers and the 105 fixed punch.

9. An apparatus for making washers, comprising a head, a movable punch movable in unison with said head, a die fixed to said head, an upper stripper movable upwardly 110 with said head but adapted to fall by gravity and positioned between said punch and die, a lower fixed punch, a lower stripper connected to said head, and means to effect relative movement between said head and said 115 fixed punch.

10. An apparatus for making washers, comprising a head, a movable punch movable in unison with said head, a die fixed to said head, an upper stripper movable upwardly 120 with said head but adapted to fall by gravity and positioned between said punch and die, a lower fixed punch, a lower stripper connected to said head, means to move said head toward said fixed punch, and springs 125 compressed by the movement of said head to effect the movement of said head away from said punch.

11. An apparatus for making washers, comprising a head, a movable punch movable 130

- in unison with said head, a die fixed to said head, an upper stripper movable upwardly with said head but adapted to fall by gravity and positioned between said punch and die, a lower fixed punch, a lower stripper connected to said head, means to move said head toward said fixed punch, springs compressed by the movement of said head to effect the movement of said head away from said punch, and means to arrest the upward movement of said upper stripper during the upward movement of said head.
12. An apparatus for making washers, comprising a base plate, a head guided with respect thereto, a punch carried by said head, a die carried by said head, a stripper head movable in said head, a stripper connected to said stripper head, a second stripper carried by said head, a punch mounted in said base plate, means to move said first punch and die toward said second punch, and resilient means to move said first punch and die away from said second punch.
13. An apparatus for making washers, comprising a base, a head movable with respect thereto, a movable punch fixed to said head, a die carried by said head, a stripper head within said head, an upper stripper keyed to said stripper head and adapted to move downwardly by gravity and to be raised by said first head, and means to effect the relative movement of said head and base.
14. An apparatus for making washers, comprising a base, spring columns rising therefrom, a head plate guided on said columns, nuts adjustably carried by said columns to limit the upward movement of said head plate, a movable punch supported by said head plate, a head connected with said head plate, a die carried by said head, a stripper movably mounted in said head, a lower stripper connected with said head, liners between said lower stripper and said head, a lower punch carried by said base, and means to effect relative movement between said head plate and said base.
15. An apparatus for making washers, comprising a base, spring columns rising therefrom, a head plate guided on said columns, nuts adjustably carried by said columns to limit the upward movement of said head plate, a movable punch supported by said head plate, a head connected with said head plate, a die carried by said head, a stripper movably mounted in said head, stripper posts by which said stripper head is guided and having means to limit the upward movement of the stripper head, said stripper posts being carried by said base, a lower stripper connected with said head,
- liners between said lower stripper and said head, a lower punch carried by said base, and means to effect relative movement between said head plate and said base.
16. An apparatus for making washers, comprising a base, a head plate, a head collar in said head plate, a punch carried by said head collar, a die, a sectional head, means to secure said sections together to lock said head plate and head collar together and to secure said die to said head sections, an upper stripper moving downwardly by gravity and adapted to be raised by said head, a lower stripper connected with and spaced from said head, a lower punch, and means to effect relative movement between said head plate and said base.
17. An apparatus for making washers, comprising a base, columns rising therefrom and having their upper ends threaded, nuts having radial slots engaging said threaded end, a head plate guided by said nut, keys carried by said head plate to engage the slots of said nut to retain them in their adjusted position, said nuts limiting the upward movement of said head plate, springs between said head plate and base, a movable punch and die operatively connected with said head plate, a fixed punch on said base, article stripping devices, and means to effect relative movement between said head plate and base.
18. An apparatus for making washers, comprising a base, a lower punch thereon, a head plate, a punch holder operatively connected with it, a punch carried by said punch holder, an upper stripping member moved upwardly by the upward movement of said said head plate and movable downwardly by gravity, a die operatively connected with said head plate, a lower stripper movable in unison with said die, and means to effect relative movement between said head plate and base.
19. An apparatus for making washers, comprising a base, a lower punch thereon, a head plate, a punch holder operatively connected with it, a punch carried by said punch holder, a punch block in said punch holder above said punch, an upper stripping member moved upwardly by the upward movement of said head plate and movable downwardly by gravity, a die operatively connected with said head plate, a lower stripper movable in unison with said die, and means to effect relative movement between said head plate and base.
